UNITED STATES PATENT OFFICE.

WILLIAM A. HEAP, OF TOPEKA, KANSAS.

DESIGN FOR A HAIRPIN.

56,557.

Specification for Design.

Patented Nov. 9, 1920.

Application filed May 4, 1920. Serial No. 378,906. Term of patent 3½ years.

To all whom it may concern:

Be it known that I, WILLIAM A. HEAP, a citizen of the United States, residing at the city of Topeka, in the county of Shawnee and State of Kansas, have invented a new, original, and ornamental Design for Hairpins, of which the following is a specification, reference being had to the accompanying drawing, forming part thereof.

In the drawings:—

Figure 1 is a front elevation of said design.

Fig. 2 an edge view of one section of the design, and

Fig. 3 an edge view of the other section of said design.

I claim:—

The ornamental design for a hairpin as shown.

WILLIAM A. HEAP.
